UNITED STATES PATENT OFFICE.

JOHN P. WILLIAMS, OF NEW YORK, N. Y., ASSIGNOR TO ELECTRIC BANK PROTECTION COMPANY, A CORPORATION OF DELAWARE.

ELECTRIC BURGLAR-ALARM SYSTEM.

1,171,997.

Specification of Letters Patent. Patented Feb. 15, 1916.

Application filed May 21, 1910, Serial No. 562,568. Renewed August 11, 1915. Serial No. 45,040.

To all whom it may concern:

Be it known that I, JOHN P. WILLIAMS, a citizen of the United States, and resident of New York, in the county and State of New York, have invented certain new and useful Improvements in Electric Burglar-Alarm Systems, of which the following is a specification.

This invention relates to burglar-alarm systems, and it has for its object to provide simple and improved means whereby the structure to be guarded will be protected in such a manner that a failure or disarrangement of one part initially subject to attack will be met by the automatic throwing into operation of parts liable to subsequent attack.

My invention comprises further improvements in the general effectiveness and economies of electric burglar-alarm systems, substantially as hereinafter described and particularly pointed out in the claims.

In the drawings—Figure 1 is a diagrammatic representation of the main parts of a burglar-alarm system embodying my improvements. Fig. 2 is a detail diagrammatic plan view of the controlling disk-mechanism. Fig. 3 is a detail edge view showing the connection of the disk-mechanism with the mechanically-operating mechanism for actuating the alarm.

Corresponding parts in all the figures are denoted by the same reference characters.

Referring to the drawings, the dotted line 1 indicates the guarded structure or main structure protected by the burglar-alarm system. The guarded structure as herein indicated may be the vault, safe, or other structure which it is desired to protect in a bank or other building, or the building or apartment itself or a part thereof. In the type of burglar-alarm systems to which my improvements particularly relate, the main guarded structure 1 is itself electrically-protected in a suitable manner so that an attack upon the same or an attempt to gain entrance thereto will sound an alarm, this electrical protection usually comprising batteries and circuits, switches and relays or other devices arranged within the guarded structure, and said circuits are connected by a cable, usually exposed and itself protected, extending to an alarm structure suitably located and containing the alarm. The alarm structure is indicated at 2, and it

usually comprises a suitable casing containing the operative parts of the alarm mechanism. The alarm structure 2 may be located at any desired point where it is intended to give an alarm by action of the electrical protective means of the main guarded structure 1, but it is usually and preferably placed upon the outside of the bank building or apartment or structure within which is located the guarded structure 1, where it is exposed to view.

My present invention comprises improvements whereby auxiliary means will serve to enable actuation of the alarm in case initial conditions of attack should for any reason throw out or cause disarrangement of the parts of the system thus initially attacked, and my improvements further comprise means for throwing out of and into circuit such alternately operative protective parts and for controlling the duration of the actuation of the alarm and the preservation of the activity of the batteries or source of electrical energy, as will be hereinafter fully described.

The alarm structure 2, in my invention, embodies a casing forming an inclosure the main walls of which consist of an outer plate, 3, which is in electrical connection with one side of a circuit, and a plurality of inner plates which are in electrical connection with the opposite side of said circuit, two of such inner plates being herein shown and respectively designated 4 and 5. Said plates are separated from each other a suitable distance, and the outer plate 3 is suitably insulated from the first inner plate 4, as at 6, and the plate 4 is suitably insulated from the second inner plate 5, as at 7. Within this structure 2 is arranged the alarm signal, which is herein shown as consisting of a suitably-mounted gong, 8.

I preferably arrange within the alarm structure or housing 2 all the parts of the electrical mechanism whereby the casing plates, 3, 4 and 5, are electrically-protected and connected in their circuit arrangements, including the battery or source of electrical energy whereby said circuits are operated, and thus the alarm structure is operatively protected entirely within itself and without dependency upon any external or supplementary source of electrical connection or current supply and independently of the

main protected structure 1 and of the circuit connections between said main protected structure and the protected alarm structure, the protective conditions being 5 thus substantially the same as those set forth and covered in my co-pending application for patent filed April 27, 1910, Serial No. 558,035, which has eventuated in a Patent, No. 1,115,359, granted Oct. 27, 1914, in which 10 the protected alarm structure constitutes in itself an independent and effective burglar-alarm system whereby the alarm cannot be disabled without the sounding thereof, in case of an attack upon the alarm structure, 15 whatever may be the electrical conditions of the main guarded structure 1 or the circuits in the connecting cable extending therefrom. In the circuit connections and arrangement thus housed within the alarm structure 2, 20 as herein shown, is comprised a battery or source of electrical energy, as at 9, an electro-magnet device, as at 10, in general of usual construction, a relay, as at 11, and a mechanical means, as at 12, for actuating a 25 hammer, as at 14, for sounding the alarm. Such mechanical means may be in the main of any suitable or adapted construction, for instance an arrangement similar to that shown in the application for patent filed by 30 M. F. Jurick, August 16, 1907, Serial No. 888,788, and as herein illustrated said mechanical means comprises a spring-motor, 15, adapted to actuate said hammer 14, which is pivotally mounted to swing in contact with the gong 8, said spring-motor being normally locked by the engagement of a revolute ratchet disk, 16, comprised in said motor mechanism, with the armature, 17, of the electro-magnet device 10, the construction and arrangement being such that 40 the operation of said armature will release said ratchet-disk and permit the operation of said motor mechanism to effect the sounding of the alarm.

45 The front of the protected alarm structure 2 is preferably of open-work construction, as is usual with these structures, to permit the emission of sound when the alarm is operated, and in the construction as herein illustrated I have shown a preferred form in which an open shutter, 18, is formed of a series of inclined plates in relatively-overlapping position, and in rear thereof is arranged a protective wire network, 19, backed by a perforated plate, 20. The front portion of the protected alarm structure 2 may be mounted and secured in any suitable manner, and preferably comprises a face-plate, 21, to which the members 18, 19 and 20 are 50 connected and which is adapted to normally contact with the outer casing plate 3, while the members 19 and 20 are respectively in electrical connection with the first inner casing plate 4 and the second inner casing plate 5, as shown at 22 and 23, and the member 20

is suitably insulated from the member 19, as at 24, and the member 19 is suitably insulated from the member 18, as at 25. It will be understood that the insertion of a metallic instrument in contact with the member 18 and the member 19 or in contact with the member 18 and the member 20 will cause the sounding of the alarm through the circuit connections hereinafter described, and that the circuit connections of the members 18, 19 and 20 may be arranged in any suitable operative manner, and it will also be understood that the general construction and arrangement is such that an attempt to drill through the casing of the protected 75 alarm structure whereby a metallic instrument is brought into contact with the outer plate 3 and the first inner plate 4 or the outer plate 3 and the second inner plate 5 will also sound the alarm through the circuit connections hereinafter described. The front portion of the protected alarm structure 2 is movably mounted with relation to the casing of the structure, for instance, it may be constituted by a hinged door comprising the members 18, 19 and 20, and to provide for sounding the alarm when said front portion is moved away from the casing of the structure 2 said movable door or front portion is provided with two sets of 85 contacts, as at 26 and 27, respectively, the first set being adapted to establish electrical circuit connection between the outer casing plate 3 and the first inner casing plate 4, while the second set 27 is adapted to establish electrical circuit connection between the outer casing plate 3 and the second inner casing plate 5. The circuit arrangement of said door contacts 26 and 27 may be in any suitable or adapted manner, and said contacts may consist of lugs, as at 28, projecting inwardly and operating to normally maintain spring contacts, as at 29, open, whereby when the lugs 28 move outwardly from the spring contacts 29 the latter are released and close the circuits of said door contacts and thus cause the sounding of the alarm. 90 In general, the circuit arrangements of the devices comprised in the protected alarm structure 2 may be of any suitable or adapted construction whereby the alarm will be sounded under the operative conditions hereinafter set forth. I have herein shown a circuit arrangement in which a wire, 30, extends from one side of the battery 9 to the outer casing plate 3, and from the other side of the battery a wire, 31, extends to the coil of the electro-magnet 10, and from the coil of said electro-magnet a wire, 32, extends to a spring contact, 33, which operates with relation to a rotary disk-mechanism for making and breaking circuits, which disk is operated by the spring-motor mechanism of the mechanical means for actuating the alarm and is comprised in my pres- 100 105 110 115 120 125 130

ent invention and improvements, substantially as will be hereinafter fully set forth. In the circuit arrangements as now described, two other spring contacts, 34 and 35, respectively operate in connection with said rotary disk-arrangement, and from these spring contacts wires respectively extend to the first inner casing plate 4 and the second inner casing plate 5, as at 36 and 37.

10 From the armature, 38, of the relay 11, extends a wire, 39, to the wire 30, and from a contact, 40, with relation to which said armature operates, extends a wire, 41, to a relay spring contact, 42, operating with relation to said rotary disk-mechanism, and wires, as at 43 and 44, comprised in a closed circuit, extend to said relay 11. The circuit arrangements as herein shown further comprise a contact, 45, carried by the armature 15 17 of the electro-magnet 10 and operating with relation to a contact, 46, which contact 45—46 is normally open, and from the contact 46 extends a wire, 47, and from said armature 17 extends a wire, 48, which wires 47 and 48 are comprised in an open circuit and lead to and are in suitable connection with the general electric protective system by which the main guarded structure 1 is itself protected.

20 I have herein shown the preferred arrangement in which all the parts of the mechanism for the protection of the casing plates of the protected alarm structure 2 are mounted within said structure 2, where- 25 by said alarm structure is completely protected electrically independent of any circuit connections or devices which may be comprised in the general electric protective system by which the main guarded structure 1 is itself electrically protected.

30 In this connection, it will be understood that the closed-circuit wires 43 and 44 and the open-circuit wires 47 and 48 lead to and are included in any general electric protective 35 system by which the main guarded structure 1 may be itself electrically protected, and that said circuits have their source of electrical energy or batteries in such general electrical protective system with which 40 they are connected, the usual arrangement of the batteries being within the main guarded structure 1, as shown in the system for the protection of such guarded structures 1 which is illustrated and de- 45 scribed in the Jurick application for patent hereinbefore mentioned. It is manifest, however, that if desired the batteries or source of electrical energy for the closed circuit including the wires 43 and 44 and the 50 open circuit including the wires 47 and 48 could be housed within the protected alarm structure 2.

55 The disk arrangement hereinbefore referred to comprises a disk, 49, adapted to be rotated by connection with one of the shafts,

50, of the spring motor mechanism for actuating the mechanical means for sounding the alarm. Said disk carries upon its face a series of segmental ways, preferably constituted by a metallic plate, as at 51, for establishing circuit connection between the spring contacts hereinbefore mentioned and which operate with relation to said disk, and the remaining surface of said disk is of insulating material, as at 52. The arrangement of the segmental ways of the plate 51 is clearly shown in Fig. 2, and this arrangement preferably comprises a larger segment, 53, adapted to conjointly receive the spring contacts 33 and 34, a smaller segment, 54, separated from the segment 53 by an insulating segmental surface space and adapted to receive the relay spring contact 42, and a larger segment, 55, extending from the segments 53 and 54 and adapted to conjointly receive the spring contacts 33, 35 and 42. In the relative arrangement, the spring contact 33 projects in one direction with relation to the disk 49, and the spring contacts 34, 35 and 42 project in the opposite direction with relation to said disk, and the contact points of all of said spring contacts are preferably on the same radial plane with relation to the axis of said disk, as shown.

55 The general operation, controlled by the action of the disk arrangement 49 in relation to the spring contacts 33, 34, 35 and 42, is such that when the mechanism is in normal position it will protect the alarm structure by means of the outer casing plate 3 and the first inner casing plate 4 and the first series of contacts 26 which are controlled by the movable front part or door of said casing, and also the circuit through the relay connection 11. When operative 60 under the conditions just stated, should the circuit through the first inner lining 4 become closed by reason of attack or in any other manner, the mechanical means for sounding the alarm will operate until the 65 rotation of the disk 49 causes the spring contact 34 to pass from the segment 53 to the insulated portion 52 at the terminal point of said segment indicated at 56, which will cut out of circuit the first inner lining 4 and connect in circuit the second inner lining 5, by reason of the concurrent passage of the spring contact 35 from the insulated portion between the segments 53 and 54 to the larger segment 55, which action will of course also 70 connect in circuit the second series of contacts 27 which are controlled by the movable front portion or door of the alarm housing 2 and will again connect in circuit the relay connection through the spring contact 35 and the second inner lining 5 instead of the previous connection through the spring contact 34 and the first inner lining 4, it being noted that the relay spring contact 42 passes directly from the smaller seg- 75 80 85 90 95 100 105 110 115 120 125 130

ment 54 to the larger segment 55. The general operation of the mechanism, as just indicated, is therefore such that in case one set of the protected plates of the alarm housing 2, for instance the outer casing plate 3 and the inner casing plate 4, becomes short circuited in any manner or for any reason, for instance by an attack or in case of an attempt to drill through the same, the disk 10 mechanism 49 changes by its revoluble action the circuit connections from said first set of plates and throws them out of circuit and in their stead throws in circuit a second set of such plates, for instance the outer casing plate 3 and the second inner casing plate 5.

It will be understood that my invention and improvements are not restricted in their application to two inner linings, as at 4 and 20 5, or to two sets of contacts which are controlled by the movable front portion or door of the alarm housing 2, but that the mechanism can be arranged for operation with relation to any desired plurality of inner 25 linings or sets of door contacts, as will be readily understood, through an arrangement of spring contacts similar to those shown at 34 and 35 and in connection with their respective inner casing plates.

30 The operation and advantages of my invention and improvements will be readily understood by those skilled in the art to which they appertain. The closed-circuit relay 11 normally operates to hold its armature 38 from the contact 40, and if the closed circuit should be opened said armature is released and establishes connection with the contact 40 and the current from the battery 9 passes through the wire 39 and through 35 the contact 40 and wire 41, the circuit being completed through the relay spring contact 42 and the plate 51 and spring contact 33 to the wire 32 and through the electro-magnet 10 and wire 31 back to the battery 9. This 40 complete circuit energizes the electro-magnet 10 and operates its armature 17 to release the ratchet or cam disk 16 and thus permit the operation of the spring-motor and mechanical means for operating the 45 alarm. Then, when the contact 42 moves off the plate 51, the armature 17 will be released and will return to normal position, and the operation of the mechanical means will stop as soon as the rotation of the ratchet-disk 50 16 brings it again in locked connection with said armature 17.

It will be noted that, when the relay 11 becomes operative by the opening of its closed circuit, the completed circuit from this relay as above described will exist as long as the relay spring contact 42 remains in contact with the segments 54 and 55 upon the revoluble disk 49, but that in case the circuit through the relay 11 is not restored 60 to its normal closed condition, whereby the

action of the mechanical means for sounding the alarm will be brought to a stop, the relay spring contact 42 will itself pass from the segment 55 to the insulated portion of the disk 49, at the point indicated at 57, by 70 the revoluble action of said disk, and that the circuit through the relay 11 will then be disconnected. It will be understood that, when the circuit through the relay 11 is out of operation, the alarm housing will be in a 75 protected status, and an attack upon the same by drilling or otherwise which short circuits the casing plates thereof will of course operate to start the mechanical means in operation to sound the alarm and 80 actuate the disk 49, through a circuit comprising the wire 30, battery 9, wire 31, electro-magnet 10, wire 32, spring contact 33, the disk-mechanism 49, and one or the other of spring contacts 34 or 35 and the connection thereof with the housing plates. If such short circuit through an attack upon the housing plates becomes continuous or is maintained and not removed, the disk 49 85 will continue in action and will operate to break the circuit which has been established through the housing plates when the spring contacts 34 or 35 pass from the segments 53 or 55 to the insulated portion of the disk 90 59 at the points indicated at 56 or 59, which action disconnects the battery 9 from the circuit extending through the housing plates and thus prevents the batteries from becoming dead by long continuance of the short circuit established by an attack upon the housing plates as above described. Therefore, under the conditions just stated, it 95 would be simply necessary to remove the short circuit conditions, re-wind the spring-motor and repair the connections, if necessary, as the battery 9 would be preserved as a direct result of the action of the cut-out of the spring contacts 34 or 35 at the points 56 or 59. It will be understood that when the battery 9 is cut out as above stated and the current is withdrawn from the electro-magnet 10, the armature 17 of the latter is released and the action of the ratchet-disk 16 with relation to its locking connection with 100 said armature operates to lock the spring-motor which actuates the mechanical means for sounding the alarm and operates the revoluble disk 49. The adjustment of the spring-motor mechanism may be such that 105 one complete operation of such a mechanism will be related to several revolutions of the ratchet-disk 16, whereby the circuit conditions governing the operation of the armature 17 of the electro-magnet 10 for the engagement of said ratchet-disk 16 will lock the spring-motor at periods intermediate of 110 one complete operation thereof, thus avoiding frequent re-winding of the spring-motor, or the adjustment may be such that the ratchet-disk 16 has but one revolution with 115 120 125 130

relation to one complete operation of the spring-motor mechanism, according to circumstances and conditions or as desired in the adaptation of the device to various conditions of use.

It will be noted that the arrangement of the segments of the revoluble disk 49 is such that the spring contact 33 will remain in contact with the segments 53 and 55 with relation to the period of contact of the spring contact 34 with the segment 53 and the period of contact of the spring contact 35 with the segment 55, before said spring contact 33 passes from the segment 55 at the point indicated at 58.

It will be understood that my improvements as herein described, for controlling the circuits of the plurality of inner casing plates of the protected structure and for successively or alternately protecting the same, are not restricted to the employment of an open circuit but are adaptable for use on a closed circuit or on a combined arrangement of both open and closed circuits, as will be readily understood by those versed in the art.

My improved means for automatically cutting out certain sections of the casing plates of the protected housing or structure and substituting other sections thereof, involving the revoluble disk-mechanism and the controlling spring contacts operating with relation thereto in their respective circuit connections, is of particular advantage in its application to the alarm housings or structures of burglar-alarm systems, as its operative action results in the controlling of the operation of the mechanical means for sounding the alarm and of the batteries for certain periods of time, whereas without this control if the mechanical means were once started the operation thereof and sounding of the alarm would continue until said means was mechanically shut off or the batteries became dead. The latter conditions are obviated by the improved controlling means and circuit arrangements as comprised in my present invention.

I do not desire to be understood as limiting myself to the detail construction and arrangement of parts or circuits as herein shown and described, as it is manifest that variations and modifications therein may be resorted to, in the adaptation of my invention to varying conditions of use, without departing from the spirit and scope of my invention and improvements. I therefore reserve the right to all such variations and modifications as properly fall within the scope of my invention and the terms of the following claims.

Having thus described my invention, I claim and desire to secure by Letters Patent:

1. In a burglar-alarm system, a structure to be guarded, a plurality of sets of casing

plates comprised in said structure, an electrically-controlled alarm mechanism, an electrical protective system comprising circuit connections with said respective sets of casing plates and with said alarm mechanism, one set of said casing plates being normally connected with and another set normally disconnected from said alarm mechanism, and means governed by the action of the circuit which controls the alarm mechanism for automatically varying said circuit connections to throw said sets of casing plates out of and into circuit respectively with said alarm mechanism.

2. In a burglar-alarm system, a structure to be guarded, a plurality of sets of casing plates comprised in said structure, an electrically-controlled alarm mechanism, an electrical protective system comprising circuit connections with said respective sets of casing plates and with said alarm mechanism, one set of said casing plates being normally connected with and another set normally disconnected from said alarm mechanism, and means governed by the action of the circuit which controls the alarm mechanism for automatically varying said circuit connections to throw said sets of casing plates out of and into circuit respectively with said alarm mechanism during the period said circuit connections are operative with relation to the casing plates.

3. In a burglar-alarm system, a structure to be guarded, a plurality of sets of casing plates comprised in said structure, an electrically-controlled alarm mechanism, an electrical protective system comprising circuit connections with said respective sets of casing plates and with said alarm mechanism, one set of said casing plates being normally connected with and another set normally disconnected from said alarm mechanism, and means governed by the action of the circuit which controls the alarm mechanism for automatically and successively varying said circuit connections to throw said sets of casing plates out of and into circuit respectively with said alarm mechanism.

4. In a burglar-alarm system, a structure to be guarded, a plurality of sets of casing plates comprised in said structure, an electrically-controlled alarm mechanism, an electrical protective system comprising circuit connections with said respective sets of casing plates and with said alarm mechanism, one set of said casing plates being normally connected with and another set normally disconnected from said alarm mechanism, and means governed by the action of the circuit which controls the alarm mechanism for automatically and alternately varying said circuit connections to throw said sets of casing plates out of and into circuit respectively with said alarm mechanism.

5. In a burglar-alarm system, a structure to be guarded, a plurality of sets of casing plates comprised in said structure, an electrically-controlled alarm mechanism, an electrical protective system comprising circuit connections with said respective sets of casing plates and with said alarm mechanism, one set of said casing plates being normally connected with and another set normally connected from said alarm mechanism, a plurality of contacts comprised in said circuit connections, and rotary mechanism governed by the action of the circuit which controls the alarm mechanism and automatically operating to vary the circuit connections of said contacts to throw said sets of casing plates out of and into circuit respectively with said alarm mechanism.
6. In a burglar-alarm system, a structure to be guarded, a plurality of sets of casing plates comprised in said structure, an electrically-controlled alarm mechanism, mechanically-operating means comprised in said alarm mechanism for actuating the alarm, an electrical protective system comprising circuit connections with said respective sets of casing plates and with said alarm mechanism, one set of said casing plates being normally connected with and another set normally disconnected from said alarm mechanism, and means actuated by said mechanically-operating means to automatically vary said circuit connections to throw said sets of casing plates out of and into circuit respectively with said alarm mechanism.
7. In a burglar-alarm system, a structure to be guarded, a plurality of sets of casing plates comprised in said structure, an electrically-controlled alarm mechanism, mechanically-operating means comprised in said alarm mechanism for actuating the alarm, an electrical protective system comprising circuit connections with said respective sets of casing plates and with said alarm mechanism, one set of said casing plates being normally connected with and another set normally disconnected from said alarm mechanism, a plurality of contacts comprised in said circuit connections, and means actuated by said mechanically-operating means to automatically vary the circuit connections of said contacts to throw said sets of casing plates out of and into circuit respectively with said alarm mechanism.
8. In a burglar-alarm system, a structure to be guarded, casing plates comprised in said structure, an electrically controlled alarm mechanism, mechanical means comprised in said alarm mechanism for actuating the alarm, an electrical protective system comprising circuit connections with said casing plates and with said alarm mechanism, some of said casing plates being normally connected with and others normally

disconnected from said alarm mechanism, and means actuated by said mechanically-operating means to automatically vary said circuit connections to throw said casing plates out of and into circuit respectively with said alarm mechanism.

9. In a burglar-alarm system, a structure to be guarded, casing plates comprised in said structure, an electrically controlled alarm mechanism, means comprised in said alarm mechanism for actuating the alarm, an electrical protective system comprising circuit connections with said casing plates and with said means for actuating the alarm, some of said casing plates being normally connected with and others normally disconnected from said alarm mechanism, and means actuated by said means for actuating the alarm to automatically vary said circuit connections to throw said casing plates out of and into circuit respectively with said alarm mechanism.

10. In a burglar-alarm system, a structure to be guarded, a plurality of sets of protective members comprised in said structure and adapted to complete electrical circuits when connection is established between the members of said respective sets, an electrically-controlled alarm mechanism, an electrical protective system comprising circuit connections with said respective sets of protective members and with said alarm mechanism, one set of said protective members being normally connected with and another set normally disconnected from said alarm mechanism, and means governed by the action of the circuit which controls the alarm mechanism to automatically vary said circuit connections to throw said sets of protective members out of and into circuit respectively with said alarm mechanism.

11. In a burglar-alarm system, a structure to be guarded, said structure comprising an outer casing member and a plurality of inner casing members, an electrically-controlled alarm mechanism, an electrical protective system comprising circuit connections with said alarm mechanism and said casing members whereby said outer casing member is a conductor of one polarity and said inner casing members are conductors of the other polarity, one of said inner casing members being normally connected with and another of said inner casing members being normally disconnected from said alarm mechanism, and means governed by the action of the circuit which controls the alarm mechanism to automatically vary said circuit connections to throw said inner casing members out of and into circuit respectively with said alarm mechanism.

12. In a burglar-alarm system, a structure to be guarded, said structure comprising an outer casing member and a plurality of inner casing members, said casing members being

relatively successively located, an electrically controlled alarm mechanism, an electrical protective system comprising circuit connections with said alarm mechanism and with 5 said casing members whereby a circuit will be completed when connection is established between said outer casing member and the first inner casing member, said first inner casing member being normally connected

10 with and the other inner casing members being normally disconnected from said alarm mechanism, and means to vary said circuit connections to successively throw said inner casing members out of and into circuit respectively with said alarm mechanism.

13. In a burglar-alarm system, a structure to be guarded, said structure comprising a plurality of successively-arranged casing plates, an electrically-controlled alarm mechanism, an electrical protective system comprising circuit connections with said alarm mechanism and with said casing plates, some of said casing plates being normally connected with and others normally disconnected 20 from said alarm mechanism, and means for varying said circuit connections to throw said casing plates out of and into circuit respectively with said alarm mechanism, whereby when two of said casing plates are in circuit connection and the circuit is completed therethrough another of said casing plates will be substituted for one of the casing plates which is in said completed circuit.

14. In a burglar-alarm system, a structure to be guarded, said structure comprising a plurality of sets of casing members, an electrically-controlled alarm mechanism, a door or movable portion for said casing structure 40 to permit access thereto, a plurality of sets of circuit contacts actuated by the movement of said access member, an electrical protective system comprising circuit connections with said alarm mechanism and with said 45 respective sets of casing members and with said respective sets of circuit contacts, one set of said casing members and of said circuit contacts being normally connected with and another of said sets normally disconnected 50 from said alarm mechanism, and means governed by the action of the circuit which controls the alarm mechanism to automatically vary said circuit connections to throw said sets of casing members and circuit contacts 55 out of and into circuit respectively with said alarm mechanism.

15. In a burglar-alarm system, a structure to be guarded, a door or movable portion for said structure to permit access thereto, an electrically-controlled alarm-mechanism, a plurality of circuit contacts actuated by the movement of said access member, an electrical protective system comprising circuit connections with said alarm mechanism and 60 with said respective circuit contacts, some of

said circuit contacts being normally connected with and others normally disconnected from said alarm mechanism, and means governed by the action of the circuit which controls the alarm mechanism to automatically vary said circuit connections to throw said circuit contacts out of and into circuit respectively with said alarm mechanism. 70

16. In a burglar-alarm system, a structure to be guarded; a plurality of sets of casing members comprised in said structure; an electrically-controlled alarm mechanism; an electrical protective system comprising circuit connections with said respective sets of casing members and said alarm mechanism, 75 said circuit connections including alarm-controlling means, one set of said casing members being normally connected with and another set normally disconnected from said alarm-controlling means; means governed by 80 the action of the means which controls the alarm mechanism to vary said circuit connections to throw said sets of casing members out of and into circuit respectively with said alarm mechanism; a normally-closed 85 circuit, 43-44, including a relay, 11; a circuit, 47-48, having a normally-open connection, 45-46, which normally-open connection is adapted to be closed by action of the alarm-controlling means; and means 90 controlled by said relay 11 whereby the alarm-controlling means is energized and the normally-open circuit is thereby closed when said normally-closed circuit is open.

17. In a burglar-alarm system, a structure to be guarded; a plurality of sets of casing members comprised in said structure; an electrically-controlled alarm mechanism; an electrical protective system comprising circuit connections with said respective sets of casing members and said alarm mechanism, 100 said circuit connections including alarm-controlling means, one set of said casing members being normally connected with and another set normally disconnected from said 105 alarm-controlling means; means governed by the action of the means which controls the alarm mechanism to vary said circuit connections to throw said sets of casing members out of and into circuit respectively with said 110 alarm mechanism; a normally-closed circuit, 43-44, including a relay, 11; a circuit, as at 47-48, having a normally-open connection, 45-46, which normally-open connection is adapted to be closed by action of the 115 alarm-controlling means; and means controlled by said relay 11 whereby the alarm-controlling means is energized and the normally-open circuit is closed when said normally-closed circuit is opened independent 120 of the circuit conditions of that part of the electrical system whereby said respective sets of casing members are in circuit with said alarm-controlling means.

18. In a burglar-alarm system, a structure 130

- to be guarded, a plurality of sets of casing members comprised in said structure, an electrically-controlled alarm mechanism, an electrical protective system comprising circuit connections with said alarm mechanism and with said respective sets of casing members, one set of said casing members being normally connected with and another set normally disconnected from said alarm mechanism, means governed by the action of the circuit which controls the alarm mechanism to automatically vary said circuit connections to throw said sets of casing members out of and into circuit respectively with said alarm mechanism, and means for automatically cutting out the battery or source of energy for the circuit connections of said casing members after a determined period of completed circuit therethrough.
19. In a burglar-alarm system, a structure to be guarded, an electrically-controlled alarm mechanism, an electrical protective system comprising a plurality of protective sections for said structure to be guarded and circuit connection with said respective sections and with said alarm mechanism, some of said protective sections being normally connected with and others normally disconnected from said alarm mechanism, and means governed by the action of the circuit which controls the alarm mechanism to automatically vary said circuit connections to throw said protective sections out of and into circuit respectively with said alarm mechanism.
20. In a burglar-alarm system, a structure to be guarded, an electrically-controlled alarm mechanism, an electrical protective system comprising a plurality of protective sections for said structure to be guarded and circuit connections with said respective sec-

tions and with said alarm mechanism, some of said protective sections being normally connected with and others normally disconnected from said alarm mechanism, and means governed by the action of the circuit which controls the alarm mechanism to automatically vary said circuit connections to alternately throw said protective sections out of and into circuit respectively with said alarm mechanism.

21. In a burglar-alarm system, a structure to be guarded, an electrical protective system comprising a plurality of protective sections for said structure to be guarded, an electrically controlled alarm mechanism, mechanically-operating means comprised in said alarm mechanism for actuating the alarm, said electrical protective system having circuit connections with said respective protective sections and with said mechanical means for actuating the alarm, some of said protective sections being normally connected with and others normally disconnected from said alarm mechanism, a battery or source of electrical energy comprised in said circuit connections, and means actuated by said mechanically-operating means to automatically vary said circuit connections to throw said protective sections out of and into circuit respectively with said alarm mechanism and to cut out the battery or source of electrical energy after a determined period of operation of said mechanical means.

In testimony whereof I have signed my name in the presence of the subscribing witnesses.

JOHN P. WILLIAMS.

Witnesses:

FREDERICK A. SMITH,
WALTER W. NORMANDY.
